UNITED STATES PATENT OFFICE.

ALPHONSO K. HARPER, OF FAIRFIELD, IOWA.

COMBINATION-TOOL.

SPECIFICATION forming part of Letters Patent No. 678,247, dated July 9, 1901.

Application filed September 29, 1900. Serial No. 31,547. (No model.)

To all whom it may concern:

Be it known that I, ALPHONSO K. HARPER, a citizen of the United States, residing at Fairfield, in the county of Jefferson and State of Iowa, have invented certain new and useful Improvements in Combination-Tools; and I do hereby declare the following to be a full, clear, and exact description of the invention, such as will enable others skilled in the art to which it appertains to make and use the same.

My invention relates to combination-tools.

In the accompanying drawings, forming a part of this specification, Figure 1 is a side elevation showing the combination-tool clamping a brush. Fig. 2 is a side elevation of the combination-tool adjusted for driving or pulling tacks or stretching carpets, the brush being removed. Fig. 3 is a bottom plan view. Fig. 4 is a detail view showing a bottom plan 20 of the casting E with the plate G removed.

Referring more particularly to the drawings, A denotes the handle, having a threaded casting B riveted thereto.

C denotes a nut or screw-ring having an internal thread adapted to register with the thread on casting B and provided on opposite sides with ears c, which are perforated to receive the bent ends of a wire clamp D.

E denotes a casting having a boss or hub 30 E' midway of its length, which is perforated to receive the shank of a conical-headed bolt F, which shank is rigidly secured to the end of the handle A. The head of the bolt is countersunk in the boss E' and is adapted to turn freely in its seat.

E² denotes a claw forming part of casting E and projects upward and rearwardly from boss E' at an angle of about forty-five degrees. Upon each side of said hub project 40 perforated lugs e e, as shown in Fig. 4.

G denotes a metal plate having a channel or slot g' arranged centrally thereof, open at its forward end and provided upon opposite sides with perforations which register with 45 perforations in the lugs e e. g g denote rivets fastening the plate G to said lugs.

The casting E has longitudinal openings upon each side of its boss, through which pass the arms of the wire yoke.

50 E³ denotes teeth formed on the rear side of the casting E and extend from end to end thereof.

To clamp a brush, the yoke is placed on the front side of the brush-head and the claw on

the rear side, as shown in Fig. 1. The handle is turned to the right, which causes the screw-ring carrying the yoke to draw it upward in the direction of the casting E, clamping the front side of the brush, while the claw takes hold of the rear side. To arrange the combination-tool as a carpet-stretcher and tack driver and puller, the handle is turned to the right until the screw-ring reaches the uppermost screw-thread on the casting B. The parts are then in the position shown in Fig. 2, the rear side of the casting having its teeth projecting, so that when the position of the handle is reversed, as shown in Fig. 2, the teeth will project sufficiently to engage the carpet.

The position of the combination-tool and relation of the parts just described are the same when the device is used as a tack driver or puller. The shank of the tack is placed in the slot, the head being placed between the edges of the slot and the under side of the boss. The tack is driven in by pressing down on the handle and simultaneously rocking or raising the handle to the vertical position. To draw a tack, the head is placed in the slot 75 and the operation reversed. It is evident by this arrangement of parts the carpet can be stretched and tacked simultaneously, as follows: A tack is first placed in the slot, the carpet caught in the teeth, stretched, the handle pressed down and forward, and as the teeth are released from the carpet the tack takes hold, retaining the carpet in the stretched position.

Having shown and described my invention, 90 what I claim, and desire to secure by Letters Patent, is—

A tool of the class described comprising a casting to receive a handle, a casting journaled to the lower end of said handle-casting 95 and provided with a series of teeth and a plate slotted to receive a tack secured to the under side of said last-named casting forward of said teeth and immediately under the handle, whereby the tack may be driven by rocking 100 the handle forward.

In testimony whereof I affix my signature in presence of two witnesses.

ALPHONSO K. HARPER.
